(57) **CLAIM**

The ornamental design for a searchlight, as shown and described.

DESCRIPTION

FIG. 1 is a front, right and top perspective view of a searchlight, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the searchlight shown in an alternate configuration of use.

FIG. 10 is another rear, left and bottom perspective view of the searchlight shown in another alternate configuration of use.

FIG. 11 is an enlarged view of detail 11 in FIG. 2; and, FIG. 12 is an enlarged view of detail 12 in FIG. 2.

The broken lines depict portions of the searchlight that form no part of the claimed design.

The dot-dash broken lines shown in FIGS. 2, 11 and 12 are for the purpose of annotating the enlargements only and form no part of the claimed design.
